Primary Examiner — Ieisha N Price

(57) **CLAIM**

The ornamental design for a fastening device as shown and described.

DESCRIPTION

Fastening Device

1.1: Front**1.2:** Back**1.3:** Left**1.4:** Right**1.5:** Top**1.6:** Bottom**1.7:** Bottom perspective**1.8:** Top perspective

Portions of the fastening device shown in broken lines do not form part of the claimed design.
